UNITED STATES PATENT OFFICE

NOEL STATHAM, OF IRVINGTON-UPON-HUDSON, NEW YORK, ASSIGNOR TO HOOKLESS
FASTENER COMPANY, OF MEADVILLE, PENNSYLVANIA, A CORPORATION OF PENN-
SYLVANIA

FLEXIBLE FASTENING DEVICE

Application filed October 26, 1927. Serial No. 228,803.

My present invention relates to flexible or automatic fasteners and the like, especially to the types employed with and embodied in shoes, bags, garments and other articles of manufacture, and aims to devise articles of the general character specified which are simple in construction, which may be readily, conveniently and economically fabricated and assembled, and which in certain of their forms necessitate the manufacture and use of only one type of fastening element, each fastening element in such forms of the present invention being adapted to serve either as the male or as the female fastening element of the flexible or automatic fasteners of the present invention. Other objects and advantages of the devices of the present invention will in part be pointed out in detail hereinafter and will in part be obvious to those skilled in the art to which the present invention relates.

Referring to the drawing, wherein I have illustrated the aforesaid illustrative embodiment of the present invention:

Fig. 1 is a view in side elevation of one of the fastener elements of the present invention;

Fig. 2 is a top plan view of the fastener element illustrated in Fig. 1 of the drawing;

Fig. 3 is a bottom plan view of the fastener element illustrated in Figs. 1 and 2 of the drawing;

Fig. 4 is a view showing the same in longitudinal section; and

Fig. 5 is a top plan view of the assembled device showing the automatic fastener embodying the fastening elements of the present invention and showing also a key or slider for operating the same, certain of the parts being shown broken away to make the showing clearer.

Referring now to the aforesaid illustrative embodiment of the present invention, and more particularly to the drawing illustrating the same, and referring especially to the fastener elements shown in Figs. 1, 2, 3 and 4 of the drawing, such fastener elements may, for example, comprise elements generally designated by reference character 10 having the conical depression 11 on one face thereof. I prefer that the fastening elements of the present invention shall embody the cooperating tape-clamping portions 13 and 14 having the jaw portions 13' and 14', respectively.

I prefer that the conical portion or elevation 12 shall substantially correspond in dimensions to the conical depression 11. This may best be accomplished by making the depression 11 and the extension 12 in a single operation, the metal portion cut out by forming the depression 11 being added to and constituting a part of the metal of which the portion 12 is made. I prefer also that the base be both of the depression 11 and of the raised portion 12 shall be equal approximately to twice the altitude of the depression 11 and the raised portion 12, respectively. I prefer also that the thickness of the sheet of which fastener elements 10 of the present invention are formed, as by stamping the same out of such a sheet with a die, shall be approximately equal to the altitude both of the depression 11 and of the raised portion 12. This latter feature is one of considerable importance since it permits a very compact arrangement of the fastener elements when assembled on their respective tapes, a feature which adds also to the strength of the completed device and to its accuracy and efficiency in operation.

The fastener elements 10 may now be assembled in two series, designated by reference characters 20 and 21, respectively. For this purpose the jaw portions 13' and 14' of the clamping jaws 13 and 14, constituting parts of the fastening elements 10, may be clamped about the beaded marginal portions 30 and 31 of the flexible supporting tapes 32 and 33, respectively. This arrangement is shown more clearly in Fig. 5 of the drawing where 40 indicates a key or slider of any suitable type for operating the automatic fas-

tening devices of the present invention embodying the fastening elements described above.

This completes the description of the aforesaid illustrative embodiment of the present invention. It will be noted that such embodiment is simple in construction and may be readily, conveniently and economically fabricated and assembled. It will also be ap-

10 parent that both flexible elements making up the complete automatic fastening device of the present invention may embody and utilize the same identical fastening elements. Due to the provision of the cooperating conical portions and the similarly shaped conical depressions in the cooperating fastening elements of the present invention, the operation of the device is rendered smooth and accurate since the conical portions are accurately cen-
15 tered by the cooperating conical depressions.

20 Other advantages and superiorities of the devices of the present invention will readily occur to those skilled in the art to which the present invention relates.

25 It may here be stated that A designates the altitude, and B the base end of the conical depression and projection whose angle is between about 60 and about 90 degrees, preferably about 90 degrees, while D represents the
30 thickness of the sheet of which the fastener element is made.

What I claim as my invention is:

1. A fastener element for automatic fas-
35 teners and the like comprising a substantial-
ly conical male fastener portion on one side
thereof and a substantially conical depression
on the other side thereof, the altitude of said
40 substantially conical male fastener portion
above the average level of the surrounding
material being substantially equal to about
one-half of the diameter of said substantial-
ly conical male fastener portion at its base.

2. A fastener element for automatic fas-
45 teners and the like comprising a substantial-
ly conical male fastener portion on one side
thereof and a substantially conical depression
on the other side thereof, the angle at
50 the apex of said substantially conical male
fastener portion being equal to about 90 de-
grees.

55 3. A fastener element for automatic fas-
teners and the like comprising a substantial-
ly conical male fastener portion on one side
thereof and a substantially conical depression
60 on the other side thereof, the altitude of
said substantially conical male fastener portion
above the average level of the surround-
ing material and of said substantially conical
65 depression being substantially equal to
about one-half of the diameter of said sub-
stantially conical male fastener portion at
its base and of said substantially conical de-
pression at its base, respectively.

70 4. A fastener element for automatic fas-
teners and the like comprising a main body

portion provided with a plurality of tape-
clamping portions adjacent one end thereof
and provided adjacent the other end there-
of with a substantially conical male fastener
portion on one side thereof and a substan-
70 tially conical depression on the other side
thereof, the angle at the apex of said sub-
stantially conical male fastener portion be-
ing equal to about 90 degrees, the altitude of
said substantially conical portion being sub-
stantially equal to half of the thickness of
75 the material of which said fastener element
is made.

5. A flexible fastening device comprising
a plurality of cooperating flexible fastener-
supporting tapes each carrying a series of
fastener elements each of which comprises a
substantially conical male fastener portion
on one side thereof and a substantially conical
depression on the other side thereof, the
80 altitude of said substantially conical male
fastener portion above the average level of
the surrounding material being substan-
tially equal to about one-half of the diameter
of said substantially conical male fastener
portion at its base.

In testimony, whereof, I have signed my
name to this specification this 11th day of
Oct., 1927.

NOEL STATHAM.
